VACUUM FILLING MACHINE

Stedman B. Hoar, Newport Beach, Calif., assignor to Natural Food Products Company, Orange, Calif., a corporation of Delaware

Application September 21, 1935, Serial No. 41,538

20 Claims. (Cl. 226—116)

My invention relates to vacuum filling-machines, for filling deaerated liquids into cans.

Heretofore, in machines of this sort, it has been customary to place, over the top of the container to be filled, a pad or stopper carrying one or more pipes for the ingress of the liquid with which the container is to be filled, and for the egress of the air from within the container. In some cases these pipes were placed one within 10 the other, so as to make a single entry through the pad. In some cases the two pipes were joined just above the pad; or, to effect the same purpose, both entered the liquid reservoir of the filling-machine, but separately, and usually at 15 different levels. The art of exhausting and filling the container by means of a hermetic pad placed over the top of the container is an old and varied one; and yet, in spite of many ingenious variants, has never been wholly successful.

20 There was an early device which partially exhausted the container, but left the reservoir under atmospheric pressure, which pressure thus forced the liquid into the container. The air conduit was connected to a vacuum system, and 25 a complicated arrangement of valves and traps was employed to prevent the excess liquid, when the container became filled, from being sucked into the vacuum system through the air conduit.

More recently, refinements in the deaeration 30 of liquid food products have necessitated that the liquid be protected from exposure to, or reentry of, air, from the time of deaeration until the liquid had been filled into the container. This has necessitated maintaining the liquid under a 35 fairly high vacuum in the reservoir of the filling-machine, and then filling it into a container initially subjected to the same fairly high vacuum. The container must be evacuated before the liquid inlet is opened, so that there will be no air-pressure within the container to blow back 40 through the liquid inlet, thus reaerating the deaerated liquid.

The evacuation pipe may pass directly from the 45 filling pad to the vacuum system; or preferably to the space above the liquid in the reservoir, and thence to the vacuum system. This latter arrangement produces initially a balanced pressure in the reservoir and in the container, so that the liquid can flow by gravity from the former to the latter.

The production and maintenance of this balanced pressure is essential to the even and uniform filling of successive containers; for obviously any excess of pressure in a container over that 55 in the reservoir will tend to prevent the liquid from flowing into it; and, if this back-pressure varies from one container to the next, the fill of the containers will vary.

The production of this balanced pressure has 60 always proved to be simple enough of attain-

ment. But its maintenance has heretofore run up against the following insuperable dilemma.

If the evacuation pipe be closed during the ingress of the liquid, the residual air in the container will be entrapped at the top of the container, together with any air which may leak in between the pad and the edge of the container. This leakage is likely to be considerable, because of the difficulty of securing a perfect seal between the pad and the frequently slightly irregular edge of the tin.

On the other hand, if the evacuation pipe be left open during the ingress of the liquid; then, if the evacuation pipe leads direct to the vacuum system, liquid is certain to be sucked into it, thus 15 damaging the pump, interfering with its proper and complete functioning, and wasting the liquid; whereas, if the evacuation pipe leads to the reservoir, mixed air and liquid find their way therethrough to mingle with the deaerated 20 air in the reservoir, and thus ruin its deaeration.

The above triple dilemma has been only particularly solved by complicated systems of traps and valves.

It is accordingly the principal object of the 25 present invention to provide a simple and uncomplicated machine which shall automatically exhaust the air from the cans to be filled, and shall then automatically fill the cans uniformly, without reaerating the liquid in the system, and 30 without sucking the liquid into the vacuum part of the system.

My invention consists in the novel parts, and in 35 the combinations and arrangements thereof, which are defined in the appended claims.

Throughout the description, the same reference-number is applied to the same member or similar members.

Figure 1 is a plan view of my revolving filling-machine.

Figure 2 is a vertical section of my machine, taken along the lines 2—2 of Figure 1.

Figure 3 is an enlarged vertical section of one of the valves shown solid in Figure 1, taken along the lines 3—3 of Figure 5.

Figure 4 is a horizontal section of this valve taken along the line 4—4 of Figure 3.

Figure 5 is a horizontal section of this valve taken along the line 5—5 of Figure 3.

Figure 6 is a diagrammatic representation of 50 the three successive positions of both levels of my valve, throughout the cycle of operation of my machine.

Figures 7, 8, 9 and 10 are vertical sections of 55 parts of four variants of my machine, the rest of each variant being as shown in Figure 2.

Beginning with Figure 2, we see that 11 is a pedestal, carrying an annular cam rail 12. 13 is the main drive-shaft from a motor (not shown). By means of bevel gears 14 and 15, this shaft 60

transmits its rotation to a vertical shaft 16, which turns the table 17 and a spillage-tray 18. This table carries a reservoir 19.

Through the spillage-tray, there reciprocate vertically a plurality of can-supports 20. Each can-support is itself supported on a roller 21, which at appropriate portions of the rail 12, raises the can support.

Depending from the table 17, and corresponding in number and position to the can-supports 20, are a plurality of valve-mechanisms 22, each carrying a sealing-pad 23.

Except between the two small arrows of Figure 1, which indicate the ingress of an empty can to the filler and the egress of a filled can therefrom (which ingress and egress may be effected in any conventional manner not shown), the cam rail 12 is of sufficient height to hold the can 24 in sealing contact with its pad 23.

For the detail of a valve-mechanism 22, turn now to Figures 3, 4 and 5, in which 23 is the sealing pad, 25 the valve-seat, 26 the valve, and 27 the valve-stem. Hole 28 is for the admission of juice, hole 29 is for the admission of air, and hole 30 for the extraction of air, i. e., is the vacuum line.

Hole 31 is an auxiliary hole, connecting with the vacuum system.

The valve has an axially located vertical hole 32, and connecting therewith a horizontal hole 33 to contact selectively: juice-hole 28, air-hole 29, and vacuum-hole 30.

The valve also has another and smaller vertical hole 34, set off-center, and connecting therewith a small horizontal hole 35, to contact, in appropriate positions, auxiliary vacuum hole 31.

In the axial center of vertical hole 32, there is secured a rod 36 carrying a headspace-gauge 37, the object of which is to displace sufficient liquid to secure a uniform headspace in the cans.

Each valve-stem 27 carries a star-wheel 38, which serves to revolve the valve to its various positions.

Turning to Figure 1, we see that a ring 39, which does not revolve with the table, supports successive pairs of pins 40, 41 and 44, to contact the points of the star-wheels 38, and thus operate the valves.

Although it forms no part of the present invention, and so is neither shown nor described, it should be remarked that it is customary to have each star-wheel 38 so connected to its corresponding pad 23, that it will remain below the level of the pins, unless there is a can beneath the pad in question, lifting up the pad, and hence lifting up the star wheel. The object of this provision is obvious, namely to prevent the exhausting of the air from nothing, and the filling of juice into nothing, when there is no can there.

Reverting now to Figure 2, we shall consider the reservoir 19. Pipe 45, which does not revolve, enters the top of the reservoir through air-tight packing 46; it leads to a vacuum pump (not shown). Pipe 47, which does not revolve, enters the top of the reservoir, through a sealed contact with pipe 45; it leads from a source of juice (not shown).

A float 48, controlling the main juice-valve 49, by means of linkage 50, maintains the juice at a constant level within the reservoir.

From the top of the reservoir 19, a vacuum-pipe 51 leads to vacuum hole 30 of each valve-mechanism 22.

From the bottom of the reservoir 19, a juice-pipe 52 leads to juice-hole 28 each valve-mechanism 22.

From the top of reservoir 19, an auxiliary vacuum-pipe 53 leads to auxiliary vacuum hole 31 of each valve-mechanism 22.

For diagrammatic simplicity, pipe 52 is shown in Figure 2 entering the valve-mechanisms 22 at a different level from pipe 51, instead of at the same level, as it actually does. Compare Figure 3.

Now comparing Figures 1 and 6, we shall see how my apparatus operates.

The empty can 24 enters at the small entering arrow of Figure 1. The table rotates clockwise in that figure. The cam-rail 12 slopes upward, forcing the can into sealing contact with pad 23, and lifting the star-wheel 38 into the level of the pins.

The valve is in position of Figure 6; open to the air, and closed to both vacuum and juice.

As the star 38 passes pins 40, they engage two of its points, and thereby rotate it 120° counter-clockwise.

The valve is now in position 2 of Figure 6: closed to the air and to the juice, but open to evacuation.

By the time that the star 38 reaches pins 41, the can 24 has been evacuated to the same degree as the reservoir 19. As the star passes pins 41, they engage two of its points, and thereby rotate it 120° counter-clockwise.

The valve is now in position 3 of Figure 6: closed to the air and to the main evacuation line 51, but open to the juice, and to auxiliary evacuation line 53. As the juice flows in, it sets up no back-pressure, for the rarified head-space air in the can, as it is compressed by the influx of the juice, is carried off through the auxiliary vacuum-line.

When the can is filled clear up to the pad 23, the can can be filled no fuller; although the juice will continue to pass through the can until it rises in auxiliary vacuum pipe 53 to the level of the juice in reservoir 19.

Pins 44 then turn the valve to position 4 of Figure 6: juice and vacuum both off, and can open to the air, thus relieving the suction on the pad, and permitting the can to lower, as the cam-rail 12 presently drops. The liquid level in the can then falls by the amount displaced by head-space-gauge 37, thus avoiding spillage.

The filled can is then carried off at the outgoing small arrow of Figure 1.

It may be asked why my provision of two vacuum lines from the valve-mechanism 22, instead of the single line of the prior art, obviates the difficulties recited at the beginning of this specification. The reason is as follows:

As already stated, the juice rises in position 3 in auxiliary vacuum-pipe 53 to the level of the juice in the reservoir 19; but, as the air was all out of the can before this occurred, there is no air to be sucked through this juice to reaerate it.

However, it will be said, this would be equally true if the main vacuum-pipe 51 were on at this time, instead of the auxiliary pipe 53. Correct—thus far. But compare what takes place, with what would take place, when we come to positions 2 and 3 with the next can.

If it were the main vacuum pipe that was full of juice, then in position 2 the air from the can would be sucked through the juice, thoroughly aerating it, and most of the thus thoroughly aerated juice would trickle down into the can to contaminate the deaerated juice later filled into it. Some of the aerated juice would be blown up into the top of the reservoir, to get into the

vacuum pump and/or contaminate the juice in the reservoir.

But in my invention, with the main vacuum-pipe 51 clear, this does not happen. Then, when we turn the valve to position 3, inasmuch as the can has already been exhausted by position 2 to the same degree of vacuum as the top of the reservoir, the juice will completely drain from the auxiliary pipe 53 into the can at the very start of the filling-operation. Thus there is not even any stagnation of juice in this pipe.

It may be asked: why not do away with the small vertical hole 34 and the small horizontal hole 35 in valve-proper 26, and then run auxiliary vacuum-line 53 into juice-hole 28, or so close to it that hole 33 will serve lines 53 and 52 simultaneously? The reason is that, in position 3, if this were the arrangement, the headspace air would pass through the incoming juice, thus aerating it. However, this objection is relatively not quite so serious as the major objections which my invention overcomes.

Thus in my invention, the cans are filled uniformly. There is no reaeration of juice. No juice finds its way into the vacuum system.

Various modifications are rendered possible in my invention, which would not be possible in the prior art. For example vacuum-pipe 51, inasmuch as it never sucks-in any juice might well run as shown at 51a in Figure 7, direct to the vacuum-pump (not shown), rather than to the top of the reservoir 19. But it is convenient to have it run to the top of the reservoir, for two reasons: (1) my arrangement facilitates equalizing the pressure in the can to that in the reservoir; and (2), in a revolving filler, my arrangement eliminates the necessity of more than one stuffing-box 46.

And my auxiliary vacuum-pipe 53 could well unite with pipe 51, and the two could enter the reservoir 19 together, provided that the juncture occurs above the level of the liquid in the reservoir, all as shown in Figure 8.

And, by the same token, my auxiliary vacuum-pipe could run, as shown at 53a in Figure 9, direct to the vacuum-pump, provided that the pipe rose above the level of the liquid in the reservoir.

The features of Figures 7 and 9 could, furthermore, be combined in one machine as shown in Figure 10.

In the variants of Figures 7, 8 and 10, in view of the fact that part of the machine rotates and part does not, it will be necessary for pipe 51a and/or pipe 53a to pass to the exhaust means by way of a stuffing-box. One such is conventionally shown, in which 60 revolves with shaft 16, and 61 remains stationary with base 11, and from which pipe 62 leads to the exhaust means (not shown).

It is to be understood that the substitution of pipe 51a for pipe 51, and of pipe 53a for pipe 53, in Figures 7, 9 and 10, occurs as to all such pipes, although shown as applied to one only.

In the claims I use the phrase "vacuum circuit" to mean one vacuum conduit, or a plurality of parallel vacuum conduits.

When, in the claims, I refer to preventing the liquid from completely filling the reservoir, and to certain lines as entering the reservoir above the liquid level thereof, this requirement would be satisfied if we were to consider a portion of pipe 47 as constituting a part of the reservoir. In such event, although the reservoir proper might completely fill, nevertheless a given maxi-

mum level could be maintained in pipe 47, and pipe 45 and lines 51 and 53 could enter pipe 47 above that level.

Having now described and illustrated one form of my invention, I wish it understood that my invention is not limited to the specific arrangement of parts hereinbefore described, or even to the variants suggested, except insofar as such limitations are specified in the appended claims.

I claim:

1. In a machine for filling liquid into containers, the combination of: a reservoir for holding liquid under a partial vacuum; means for admitting liquid to the reservoir, and for preventing the liquid from completely filling the reservoir; means for exhausting the reservoir; means, at a level below the level of the liquid in the reservoir, for sealing a container against the atmosphere; a valve, having three selective positions, namely, (1) open to the air conduit hereinafter described and closed to the liquid conduit hereinafter described and to both of the vacuum lines hereinafter described, (2) open to the main vacuum line and closed to the air and liquid conduits and to the auxiliary vacuum line, and (3) open to the liquid conduit and to the auxiliary vacuum line and closed to the air conduit and to the main vacuum line; a conduit connecting the valve to the air; a main vacuum line, and a distinct auxiliary vacuum line, each separately connecting the valve to the reservoir above the liquid level therein; a liquid conduit connecting the valve to the reservoir below the liquid-level therein; a conduit connecting the valve to the sealed container; and automatic means for successively, with respect to each container to be filled, sealing the container, setting the valve to these three positions in the following order, namely: 1, 2, 3, 1, and then unsealing the container.

2. In a machine for filling liquid into containers, the combination of: a reservoir for holding liquid under a partial vacuum; means for admitting liquid to the reservoir, and for preventing the liquid from completely filling the reservoir; means for exhausting the reservoir; means, at a level below the level of the liquid in the reservoir, for sealing a container against the atmosphere; a valve; a conduit connecting the valve to the air; a main vacuum line, and a distinct auxiliary vacuum line, each separately connecting the valve to the reservoir above the liquid level therein; a liquid conduit connecting the valve to the reservoir below the liquid-level therein; and a conduit connecting the valve to the sealed container.

3. In a machine for filling liquid into containers, the combination of: a reservoir for holding liquid under a partial vacuum; means for admitting liquid to the reservoir, and for preventing the liquid from completely filling the reservoir; means, at a level below the level of the liquid in the reservoir, for sealing a container against the atmosphere; a valve, in the sealing means, having three selective positions, namely, (1) open to the air conduit hereinafter described and closed to the liquid conduit hereinafter described and to both of the vacuum lines hereinafter described, (2) open to the main vacuum line and closed to the air and liquid conduits and to the auxiliary vacuum line, and (3) open to the liquid conduit and to the auxiliary vacuum line and closed to the air conduit and to the main vacuum line; a conduit connecting the valve to the air; a main vacuum line, and a distinct auxiliary vacuum line, each separately connecting the valve to

the reservoir above the liquid level therein; a liquid conduit connecting the valve to the reservoir below the liquid-level therein; and a conduit connecting the valve to the sealed container.

gresses, for successively sealing the container, setting the valve means to these three positions in the following order, namely: 1, 2, 3, 1, and then unsealing the container; the auxiliary vacuum line being characterized by passing above the level of the liquid in the reservoir.

9. In a machine for filling liquid into containers, the combination of: a reservoir for holding liquid under a partial vacuum; means for admitting liquid to the reservoir, and for preventing the liquid from completely filling the reservoir; means for exhausting the reservoir; means, at a level below the level of the liquid in the reservoir, for sealing a container against the atmosphere; a valve having three selective positions, namely, (1) open to the air conduit hereinafter described and closed to the liquid conduit hereinafter described and to both of the vacuum lines hereinafter described, (2) open to the main vacuum line and closed to the air and liquid conduits and to the auxiliary vacuum line, and (3) open to the liquid conduit and to the auxiliary vacuum line and closed to the air conduit and to the main vacuum line; a conduit connecting the valve to the air; a main vacuum line and an auxiliary vacuum line each connecting the valve to a common entry to the reservoir above the liquid level therein; a liquid conduit connecting the valve to the reservoir below the liquid-level therein; a conduit connecting the valve to the sealed container; and automatic means for successively, with respect to each container to be filled, sealing the container, setting the valve to these three positions in the following order, namely: 1, 2, 3, 1, and then unsealing the container.

10. In a machine for filling liquid into containers, the combination of: a reservoir for holding liquid under a partial vacuum; means for admitting liquid to the reservoir, and for preventing the liquid from completely filling the reservoir; means for exhausting the reservoir; means, at a level below the level of the liquid in the reservoir, for sealing a container against the atmosphere; a valve; a conduit connecting the valve to the air; a main vacuum line and an auxiliary vacuum line each connecting the valve to a common entry to the reservoir above the liquid level therein; a liquid conduit connecting the valve to the reservoir below the liquid-level therein; and a conduit connecting the valve to the sealed container.

11. In a machine for filling liquid into containers, the combination of: a reservoir for holding liquid under a partial vacuum; means for admitting liquid to the reservoir, and for preventing the liquid from completely filling the reservoir; means for exhausting the reservoir; means, at a level below the level of the liquid in the reservoir, for sealing a container against the atmosphere; a valve, having three selective positions, namely, (1) open to the air conduit hereinafter described and closed to the liquid conduit hereinafter described and to both of the vacuum lines hereinafter described, (2) open to the main vacuum line and closed to the air and liquid conduits and to the auxiliary vacuum line, and (3) open to the liquid conduit and to the auxiliary vacuum line and closed to the air conduit and to the main vacuum line; a conduit connecting the valve to the air; a main vacuum line and an auxiliary vacuum line each connecting the valve to a common entry to the reservoir above the liquid level therein; a liquid conduit connecting the valve to the reservoir below the liquid level therein; and a conduit connecting the valve to the sealed container.

12. In a machine for filling liquid into containers, the combination of: a reservoir for holding liquid under a partial vacuum; means for admitting liquid to the reservoir, and for preventing the liquid from completely filling the reservoir; means for exhausting the reservoir; means, at a level below the level of the liquid in the reservoir, for sealing a container against the atmosphere; a valve, having three selective positions, namely, (1) open to the air conduit hereinafter described and closed to the liquid conduit hereinafter described and to both of the vacuum lines hereinafter described, (2) open to the main vacuum line and closed to the air and liquid conduits and to the auxiliary vacuum line, and (3) open to the liquid conduit and to the auxiliary vacuum line and closed to the air conduit and to the main vacuum line; a conduit connecting the valve to the air; a main vacuum line and an auxiliary vacuum line each connecting the valve to a common entry to the reservoir above the liquid level therein; a liquid conduit connecting the valve to the reservoir below the liquid-level therein; a conduit connecting the valve to the sealed container; and means for carrying containers progressively through the machine, and as each container progresses, for successively sealing the container, setting the valve to these three positions in the following order, namely: 1, 2, 3, 1, and then unsealing the container.

13. In a machine for filling liquid into containers, the combination of: a reservoir for holding liquid under a partial vacuum; means for admitting liquid to the reservoir; exhausting means; means for sealing a container against the atmosphere; valve means having three selective positions, namely, (1) open to the air conduit hereinafter described and closed to the liquid conduit hereinafter described and to both of the vacuum lines hereinafter described, (2) open to the main vacuum line and closed to the air and liquid conduits and to the auxiliary vacuum line, and (3) open to the liquid conduit and to the auxiliary vacuum line and closed to the air conduit and to the main vacuum line; a conduit connecting the valve means to the air; a main vacuum line and an auxiliary vacuum line each connected to the valve means, and exhaustible by the exhausting means; a liquid conduit connecting the valve means to the reservoir below the liquid-level therein; a conduit connecting the valve means to the sealed container; and automatic means for successively, with respect to each container to be filled, sealing the container, setting the valve means to these three positions in the following order, namely: 1, 2, 3, 1, and then unsealing the container.

14. In a machine for filling liquid into containers, the combination of, a reservoir for holding liquid under a partial vacuum; means for admitting liquid to the reservoir; exhausting means; means for sealing a container against the atmosphere; valve means having three selective positions, namely, (1) open to the air and closed to the liquid conduit hereinafter described and to both of the vacuum lines hereinafter described, (2) open to the main vacuum line and closed to the air and liquid conduits and to the auxiliary vacuum line, and (3) open to the liquid conduit and to the auxiliary vacuum line and closed to the air conduit and to the main vacuum line; a conduit connecting the valve means to the air; a main vacuum line and an auxiliary vacuum line each connected to the valve means, and exhaust-

ible by the exhausting means; a liquid conduit connecting the valve means to the reservoir below the liquid-level therein; a conduit connecting the valve means to the sealed container; and 5 means for carrying containers progressively through the machine, and as each container progresses, for successively sealing the container, setting the valve means to these three positions in the following order, namely: 1, 2, 3, 1, and then 10 unsealing the container.

15. In a machine for filling liquid into containers, the combination of: a reservoir for holding liquid under a partial vacuum; means for admitting liquid to the reservoir; exhausting means; a vacuum circuit, exhaustible by the exhausting means; means for sealing a container against the atmosphere; valve means having three selective positions, namely, (1) open to the air conduit hereinafter described and closed to 15 the liquid conduit hereinafter described and to the vacuum circuit, (2) open to the vacuum circuit and closed to the air and liquid conduits, and (3) open to the liquid conduit and to the vacuum circuit and closed to the air conduit; a conduit connecting the valve means to the air; a liquid conduit connecting the valve means to the reservoir below the liquid-level therein; a conduit connecting the valve means to the sealed container; and automatic means for successively 20 25 30 35 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470

machine, and as each container progresses, for successively sealing the container, setting the valve means to connect the vacuum circuit to the sealed container, setting the valve means at least once to connect the liquid conduit to admit liquid to the container, and simultaneously to connect the vacuum circuit to the sealed container, setting the valve means to close the vacuum circuit and the liquid conduit and open the release conduit, and finally unsealing the container.

18. In a machine for filling liquid into containers, the combination of: a reservoir for holding liquid constantly under partial vacuum; means for sealing a container against the atmosphere; means for reducing pressure within said container before admitting liquid thereto; means for then conveying liquid from the reservoir to the container; means operable, while the liquid conveying means is operating, to maintain the reduction of pressure in the container; and means for then unsealing the container; the reduced-pressure-maintaining means serving also to receive any overflow from the filled container and to deliver said overflow to the next succeeding container which occupies the place of the first-mentioned container.

19. In a machine for filling liquid into containers, the combination of: a reservoir for holding liquid constantly under partial vacuum; a single valve element, automatic in its movement for each container passing through the machine; means for sealing a container against the atmosphere; means for reducing pressure within said container before admitting liquid thereto; means for then conveying liquid from the reservoir to the container; means operable, while the liquid conveying means is operating, to maintain the reduction of pressure in the container; and means for then unsealing the container; the reduced-pressure-maintaining means serving also to receive any overflow from the filled container and to deliver said overflow to the next succeeding container to occupy the place of the first-mentioned container; the last four mentioned means being operative in the sequence indicated through the movement of the valve element.

20. In a machine for filling liquids into containers the combination of: exhausting means; a liquid reservoir, exhaustible by the exhausting means; means for sealing a container against the atmosphere; a two-part vacuum circuit, exhaustible by the exhausting means; a circuit for conveying liquid from the reservoir to the container; means for successively connecting these circuits to the container and disconnecting them therefrom, in such order that the vacuum circuit will exhaust the container before the liquid is conveyed to the container, that a part of the vacuum circuit, while still connected to the exhausting means, will receive excess liquid from the container while said liquid conveying circuit is operative, and that this part of the vacuum circuit will be closed to each container during the exhaustion thereof until the liquid conveying circuit is opened to that container, thereby preventing re-entrance of the liquid thus trapped in this part of the vacuum circuit; and means for unsealing the container, without thereby releasing the vacuum in the reservoir.

STEDMAN B. HOAR.
